DESIGN FOR A PIANO OR SIMILAR ARTICLE

Jacob L. Krasnick, Holly, Mich., assignor to Grinnell Bros., Detroit, Mich., a corporation of Michigan

Application July 11, 1936, Serial No. 63,788

Term of patent 3½ years

To all whom it may concern:

Be it known that I, Jacob L. Krasnick, a citizen of the United States of America and residing at Holly, in the county of Oakland and State of Michigan, have invented a new, original, and ornamental Design for a Piano or Similar Article, of which the following is a specification, reference being made to the accompanying drawings, forming part thereof.

Fig. 1 is a front elevational view of a piano showing my new design and illustrating the same with the case open.

Fig. 2 is a side elevational view thereof.

I claim:

The ornamental design for a piano or similar article substantially as shown.

JACOB L. KRASNICK.
